UNITED STATES PATENT OFFICE.

CHARLES B. RICH, OF EAST WHITMAN, AND JOHN REED, OF WHITMAN,
MASSACHUSETTS.

SHANK-STIFFENER MACHINE.

SPECIFICATION forming part of Letters Patent No. 885,489, dated October 29, 1901.
Application filed June 18, 1901. Serial No. 64,432. (No model.)

To all whom it may concern:

Be it known that we, CHARLES B. RICH, a citizen of the United States, residing at East Whitman, and JOHN REED, a subject of the King of Great Britain, residing at Whitman, in the county of Plymouth, State of Massachusetts, have invented a certain new and useful Improvement in Shank-Stiffener Machines, of which the following is a specification, reference being had therein to the accompanying drawings.

The invention consists in various features of improvement in machines for attaching steel strips or "steels" to the bodies of leather-board or other material of shank-stiffeners. These features we will proceed to explain with the aid of the drawings, in which latter we have illustrated the same embodied in the best forms that we have yet contrived.

In the drawings, Figure 1 shows in front elevation a shank-stiffener machine having our invention embodied therein. Fig. 2 shows the same in end elevation. Fig. 3 shows the same in plan, the tack-supplying devices being removed. Fig. 4 is a detail view in vertical section on substantially the plane indicated by the dotted line 4-4, Fig. 3, looking in the direction indicated by the arrows adjacent to the ends of such line. Fig. 5 is a similar view in section on line 5-5, Fig. 3, the driving arrangements being omitted. Fig. 6 is an end elevation, partly sectional, of the parts shown in Fig. 5. Figs. 7 and 8 are views in vertical section, showing mainly the devices for placing tacks in the holes of the steels and representing said devices in different positions. Fig. 9 is a plan view of certain portions of the said devices. Fig. 10 is a plan view of details of one of the tack-feeds.

The frame of the machine is represented as comprising, essentially, opposite side frames or uprights 11 and a table or platform 2, supported thereby, a suitable driving-shaft 3 being shown mounted in bearings in said side frames or uprights 11 and being represented as provided with a band-pulley 4 to serve in the transmission of driving power to the said shaft.

The supply of leather-board body-blanks to which steels are to be attached will be stacked in practice in suitable guides—such, for in-

stance, as those indicated at 55—having feet 66 resting on table 2 and attached to the latter by bolts 77, adjustment of the said guides nearer to or farther from each other to suit variations in the lengths of the body-blanks to be dealt with being provided for by means of slots 88 in the base portions of said feet 66, through which slots said bolts 77 pass into the table 2. A body-blank is represented in position between the said guides 55 in dotted lines at a in Fig. 3.

The feed of the body-blanks a successively into position to have the steels attached thereto may be effected in any convenient manner in practice. It is provided for in the present instance by means of feed-bars 99, working at the upper surface of table 2. The said feed-bars are herein represented as extending at all times beneath the position of the stack of body-blanks, so that the bottom one of said blanks shall rest thereon, the feed-bars being suitably constructed to engage with the said bottom blank and carry the latter along with them in their forward movement. As a convenient means of enabling the feed-bars thus to engage with the bottom blank they are shown as furnished with forwardly-projecting spurs or teeth which bite into the said blank sufficiently to carry the latter with them in their forward movement, the said spurs or teeth slipping beneath the stack of body-blanks in the rearward or retracting movement of the feed-bars. For the convenient actuation of the feed-bar they are represented as bolted at 1010 to a slide 11, working in guideways or slots, as at 12, in extensions of table 2, the said slide being connected by a link 13 with a lever 14, carrying a pin or roll working in a groove in one side 90 of a cam-disk 15, made fast on shaft 3.

The steels to be attached to the body-blanks a are stacked between guides, as at 16 16, suitably supported above the table 2, near the rear thereof. A steel is shown in dotted outline at b, Fig. 3, in position between said guides, the tack-holes thereof being indicated at c c. For the purpose of advancing the steels successively from the base of the stack toward the place at which they are attached to the body-blanks we provide feed-bars 17 17, to which in practice a reciprocating move-

ment is communicated in convenient manner. Herein the said feed-bars are represented as bolted at 18 18 to a slide 19, working in guide-slots 20 in extesions provided 5 on table 2, the said slide being loosely connected at 21 with a lever 22, carrying a pin or roll working in a groove in the face of cam 15 opposite the face of said cam containing the groove serving in the actuation of lever 14. The steels 6 are liable to warp in being hardened and tempered. This renders a feed device acting directly against a side edge of the bottom steel of the stack to push said steel transversely out of the position normally occupied thereby toward the place at which the attachment to the body-blank is effected more or less unreliable in action. The engaging portion of the feed device in such case requires to stand no higher than 20 the upper surface of the bottom steel in order to avoid engagement of the same with two steels at one time. Hence when the edge of the bottom steel is warped the feed device is likely to pass in under the same with a failure to feed as the result. In order to prevent misfeeds, we provide means for separating the bottom steel from the one next above the same in readiness to be taken by a feed device acting against one edge thereof 25 to feed the same transversely toward the place at which the attachment of the same to a body-blank is to be effected. In order to accomplish the separation of the bottom steel, we support the same in the stack merely 30 at its extreme ends, as indicated in Fig. 4, the said ends resting upon comparatively narrow ledges 23 and 24 at the lower ends of the respective guides 16 16. Ledge 23 is a little higher than ledge 24, as in said figure, 35 and hence a steel resting on said ledges is supported in a somewhat inclined position, with one end thereof slightly higher than the other one. Immediately above the ledge 24 is located a gage-plate 25, the lower end of 40 which is separated from the said ledge by a vertical space just enough greater than the thickness of a steel to permit the corresponding end of the bottom steel of the stack to slip under the same when such steel is moved 45 endwise. For the purpose of effecting an endwise movement of the bottom steel sufficient to carry one end thereof in between the ledge 24 and gage-plate 25 and cause the other end thereof to drop off the ledge 23 and 50 land on a ledge 26, immediately adjacent the said ledge 23, but at a lower level, we provide a pusher 27, Figs. 3 and 4, constructed and arranged to engage with the higher end of the said steel. A convenient means of communicating to the said pusher 27 the necessary 55 short reciprocatory movement is shown in Fig. 3, it comprising an arm 28, having pusher 27 attached thereto and itself pivoted, as at 29, at its outer end to a fixed support, the 60 said arm having an oblique cam-slot 30 therein receiving a pin or roll 31, carried by feed-slide 19. As feed-slide 19 moves back into

its retracted position the pin or roll 31, carried thereby, working in cam-slot 30 causes arm 28 to swing in a direction to advance the 70 pusher 27, so as to push the bottom steel endwise, as described above, causing one end thereof to pass under gage-plate 25 and project at one end of the stack and the other end thereof to drop from ledge 23 to ledge 26, by 75 which such end is separated a short distance vertically from the next steel above the same, as shown in Fig. 4. The opposite ends of the bottom steel have now been separated from the next succeeding steel or steels and caused 80 to take positions in which the side edge of the said bottom steel at such ends may readily be engaged by the feed-bars 17 17 without danger of misfeed. The engaging portions of the feed-bars 17 17 may also be formed of any 85 desired height. By supporting the steels merely at their ends the warping of the steels is rendered of no consequence—that is to say, is prevented from acting to occasion such a displacement of the steels as would interfere 90 with the engagement and movement of the same by pusher 27. Said pusher, which corresponds substantially in height with the bottom steel resting on ledge 23, is bound to engage the end of said steel in moving inward 95 and to push the said end off the ledge 23. The feed-bars 17 17 push the bottom steel 6 along the ledges 24 and 26 and into position to have tacks introduced into its holes c c. Each steel in turn as thus pushed transversely 100 pushes the next preceding steel ahead of it onto continuations 32 32 of said ledges 24 26. The said continuations are mounted upon horizontal pivots 33 33, Fig. 5, with capacity to swing in vertical planes and have connected therewith springs, as at 34 34, acting to hold them uplifted into the horizontal position which normally is occupied thereby. The said continuations are arranged to yield and turn downwardly when acted upon by a suitable 110 force. A steel being in position upon the yielding steel-supports 32 32, above a leather-board body-blank a, with its holes occupied by tacks, the descent of the tack-drivers 35 35 causes them to carry down the said steel, forcing the 115 steel-supports 32 32 to swing downward, carrying the steel down against the body-blank and driving the tacks into the latter, thereby attaching steel and body-blank together. As the steel escapes from the steel-supports the 120 latter rise into normal position, where they remain in readiness to receive the next steel when it is advanced onto them. In the descent of the drivers they make contact with the tops of the flat heads of the tacks which 125 occupy the holes of the steel which is in position beneath the drivers. Thereby the flat heads of the tacks are clamped by the drivers against the steel and the tacks are held firmly in position for being driven. As the drivers 130 continue their descent they force the steel down upon the body-blank, the yielding continuations of the guideways—i. e., the steel-supports 32 32—giving way to the pressure.

The said continuations or steel-supports hold the steel and position the same until the points of the tacks have partly entered the body-blank. Then they fly back into normal position. In this manner the steel is held back against the pressure of the drivers in such manner as to keep the tacks firmly in the required position until the same have been partially driven.

- 10 For the actuation of the drivers 35 35 they are attached to a vertically-movable bar 36, having connected therewith guide-rods 37 37, working in tubular guides 38 38 on the uprightsides of the machine-frame, the said bar 15 36 having connected therewith connecting-rods 39 39, formed with straps 391 391, fitting the eccentric 40 40 on the shaft 3.

In practice suitable provision will be made for supplying tacks and delivering them in 20 succession to be driven. We have represented in the drawings convenient arrangements for the purpose comprising principally hoppers 41 41, attached to the upper portions of the side frames 11, chutes 42 42, leading downward from the said hoppers 41 41, and feed-plates 43 43, working vertically within the said hoppers for the purpose of lifting tacks into position to pass onto the chutes 42 42, the said feed-plates having their upper edges 25 grooved to receive the tacks and also having the said upper edges inclined, so that the tacks may slide therefrom onto the upper ends of the chutes 42 42, the said feed-plates being connected, as at 44 44, with projections 30 depending from the bar 36, and thereby being actuated as the said bar rises and falls. A suitable arrangement of escapement devices for causing the tacks to be delivered singly at the lower end of each chute is represented in plan in Fig. 10, which shows portion 35 of one chute and a number of tacks supported thereby. The escapement-slides 45 45 are represented as operated in one direction by means of cam-pieces 46 46, attached to the bar 36, and in the other direction by means of springs 47 47, acting in opposition to the cam-pieces.

48 48 are guide-tubes attached to the lower ends of the chutes 42 42.

- 50 For the purpose of introducing the tacks properly into the holes *c c* of the steel *b* a guide 49 (see more particularly Figs. 5, 7, 8, and 9) is employed in connection with each tube 48. Each guide 49 is provided with a 55 passage 50 therethrough, and in the normal position of the guide 49 the top of this guide-passage 50 is beneath the tube 48 in position to receive a tack as it drops point foremost from the said tube. For the purpose of 60 centering the tack, the guide 49 is furnished at the bottom of the passage 50 with two jaws 51 52. The jaw 51 is formed with a V-shaped notch which receives the jaw 52, the latter being of a corresponding shape to enable it 65 to fit and work within the notch of the jaw 51. The apex of the jaw 52 is truncated and slightly concaved in order that when the

jaws are close together an opening may exist into which the point of a descending tack may enter. These jaws operate to place the 70 point of the tack in line with the tack-hole *c* in the steel *b*, so as to insure the entrance of the said point into the said tack-hole at the proper time.

The holes which are formed in the ends of 75 the steels for the reception of the tacks vary in position in different steels more or less in practice—that is to say, the said holes are located at the middle of the width of the steel; but their positions in the lengths of 80 different steels vary. In order, therefore, to enable the tack to find the tack-holes *c c*, the guides 49 49 are given a movement lengthwise of the steel *b*, this movement being sufficient in extent to take care of the widest 85 range of variation in the position of the holes in different steels. As the guides move lengthwise of the steel after receiving tacks they carry such tacks to the holes in the steel, and as soon as the tacks arrive over 90 the said holes they drop into the latter. For the actuation of the guides 49 49 they are connected with the slides 53 53, the latter working in guideways at 54 54 and being here represented as connected by means of rods 95 55 55 with levers 56 56, operated in one direction by means of side cams 57 57 on the shaft 3 and in the other direction by means of springs 58, one of which is represented in Fig. 2. In order to enable the guides to conform to any 100 curvature of the steel, they are loosely or pivotally connected, as at 59, with the slides 53. (See Figs. 7, 8, and 9 more especially.) In order to insure the entrance of the point of a tack into the tack-hole in steel when said point 105 reaches the said tack-hole in the movement of the guide 49 the passage 50 through the said guide slants downward and in the direction in which the guide moves in carrying the tack to the tack-hole. In the present 110 case such movement is inward from the end of the steel toward the middle of the length thereof, and consequently the passage 50 inclines downward and inward. A tack occupying the said passage 50 inclines point foremost—that is to say, the point thereof inclines forward toward the hole in the steel. When in the inward movement of the guide the point of the tack enters the hole in the steel, the continued movement of the guide operates 115 120 with a tendency to cause the tack to stand upright in the said hole, thus facilitating greatly the readiness with which the tack will enter or drop into the said hole. If the passage 50 in the guide were vertical, the friction of the point of the tack in sliding along the upper surface of the steel would tend to cause the tack to incline reversely, and in consequence the tack would be likely to bind over the edge of the tack-hole in the steel 130 and the descent of the tack into the tack-hole would be made more difficult.

For the purpose of freeing the tack the jaws 51 52 are separated at the beginning of the

inward movement of the guide 49. To this end the jaw 51 is made movable relatively to the guide 49 and the other jaw 52, and at the beginning of the said inward movement of the guide it is separated from the jaw 52 by a quick movement. Herein the movable jaw 51 is shown provided on the recurved inner end of a strip 511, surmounting the guide 49 and formed with an opening 512 therethrough, which last in the closed position of the jaws registers with the passage 50 in the guide, so that a tack in descending from the tube 48 passes through the said opening 512 on its way to the passage 50 of the guide. Strip 511 is connected by link 60 with a lever 61, mounted on a fixed pivot at 62 and loosely connected with the slide 53 by means of a pin or screw 63, projecting from the said slide and working in a longitudinal slot that is formed in the said lever 61. By means of the said screw or pin, the lever, and the link the movement of the slide 53 is transmitted in accelerated ratio to the strip 511. This takes the movable jaw away from the tack, the latter, however being held back against the concave end of the jaw 52 in consequence of the friction of the point of the tack against the upper surface of the steel b. The jaw 52 is movably connected with the guide 49, being arranged to slide upon the latter and being backed up by a light spring 64 to hold the said jaw in its normal position. The said jaw is capable of yielding upon the application of slight force thereto, and in operation as soon as the tack enters the tack-hole the resistance which the tack offers against the continued movement of the jaw 52 with the guide 49 serves to arrest further advance of the jaw 52.

Each body-blank a in turn as it is pushed forward by the feed-bars 99 pushes ahead of it the shank-stiffener which has been completed by the attachment of the steel thereto. The finished shank-stiffeners drop off the edge of the bed or table 2 onto a traveling belt or conveyer-apron 65, which is shown in part in Figs. 1 and 2, but omitted from Fig. 3 for the sake of clearness, the said apron passing around a roll 66 on a shaft 67, which is driven by a band 68 from the main shaft 3. While on the belt or conveyer-apron 65 the shank-stiffeners may be inspected and the defective ones removed.

We claim as our invention—

1. In a shank-stiffener machine, in combination, means for attaching steels to body-blanks, means for supporting a stack of steels, means to separate the first steel of said stack from the next, and a feed device acting against the edge of said first steel after the separation to move the same transversely in the machine toward the said attaching means, substantially as described.
2. In a shank-stiffener machine, in combination, means for attaching steels to body-blanks, means for supporting a stack of steels, means to cause the first steel to pro-

ject endwise at one end of said stack and effect separation vertically between the other end of said steel and the remainder of the stack, and a feed device acting against the thus-separated end portions of said bottom steel to feed the latter transversely toward the said attaching means, substantially as described.

3. In a shank-stiffener machine, in combination, means for attaching steels to body-blanks, guides for a stack of steels, a support for one end of the first steel, ledges of different elevation at the other end of the stack, a pusher to move the first steel endwise and shift the rear end thereof from the higher of the said ledges to the lower, and a feed device to engage with the edge of the first steel and move it transversely in the machine toward the said attaching means, substantially as described.

4. In a shank-stiffener machine, in combination, a support for a body-blank, steel-attaching devices, and yielding steel-supports to uphold a steel above said body-blank, said steel-supports giving way under pressure of the attaching devices, substantially as described.

5. In a shank-stiffener machine, in combination, a support for a body-blank, means to supply tacks to the tack-holes of a steel, tack-drivers, and yielding steel-supports to uphold the steel above said body-blank, arranged to give way under pressure of the drivers upon the heads of the tacks, whereby the drivers are caused to hold the tacks firmly in position for being driven and the steel is positioned in being attached, substantially as described.

6. In a shank-stiffener machine, in combination, guides for a stack of steels, means for introducing tacks into the holes of a steel in position to receive the same, tack-driving means, supports along which a steel may be slid from said stack, and feeding devices operating to carry a steel along said supports from said stack into position for receiving tacks, all arranged to cause said steel in driving at such position to push forward the next preceding steel into position in connection with such tack-driving means proper for being attached to a body-blank, substantially as described.

7. In a shank-stiffener machine, in combination, guides for a stack of steels, means for introducing tacks into the holes of a steel in position to receive the same, tack-driving means, guides along which a steel may be slid from said stack, spring-supported steel-supports for supporting a steel while being attached to a body-blank, and feeding devices operating to carry a steel from said stack along said supports into position for receiving tacks, all arranged to cause said steel in driving at such position to push forward the next preceding steel onto said spring-supported steel-supports, into position in connection with such tack-driving means for being at-

tached to a body-blank, substantially as described.

8. In a shank-stiffener machine, in combination, guides for a stack of steels, ledges 23 and 24 for supporting opposite ends of the said stack, a ledge 26 at a lower level than ledge 23, a pusher to engage with the steel resting against ledges 23 24 and push the same endwise, whereby to cause the steel to drop to ledge 26, and a feed device engaging with the side edge of the first steel at the ends thereof after such ends have been separated from the succeeding steel by the endwise movement, substantially as described.

9. In combination, supports for a steel, a guide to support a tack with the point thereof resting against the surface of said steel, and means to move said guide lengthwise of the steel to cause the tack to find the tack-hole therein, substantially as described.

10. In combination, supports for a steel, a guide to support a tack with the point thereof resting against the surface of said steel, a slide with which said guide is loosely connected to enable the guide to follow the surface of the steel, and means for operating said slide to move said guide lengthwise of the steel to cause the tack to find the tack-hole therein, substantially as described.

11. In combination, supports for a steel, a guide having a passage to receive a tack and support the latter with the point thereof resting against the surface of the steel, said guide having opposing jaws to center the tack-point, means to move said guide lengthwise of the steel to cause the tack to find the tack-hole therein, and means to open and close said jaws, substantially as described.

12. In combination, supports for a steel, a guide having a passage to receive a tack and support the latter with the point thereof resting against the surface of the steel, said guide having opposing jaws to center the tack-point, a slide with which the said guide is loosely connected to enable the guide to follow the surface of the steel, means for operating said slide to move said guide lengthwise of the steel to cause the tack to find the tack-hole therein, and means to open and close said jaws, substantially as described.

13. In combination, supports for a steel, a

guide having a sloping or inclined passage to receive a tack and support the latter with the forwardly-inclined point thereof resting against the surface of said steel, and means to move said guide lengthwise of the steel to cause the tack to find the tack-hole therein, substantially as described.

14. In combination, supports for a steel, a guide having a sloping or inclined passage to receive a tack and support the latter with the forwardly-inclined point thereof resting against the surface of said steel, a slide with which said guide is loosely connected to enable the guide to follow the surface of the steel, and means for operating said slide to move said guide lengthwise of the steel to cause the tack to find the tack-hole therein, substantially as described.

15. In combination, supports for a steel, a guide having a passage to receive a tack and support the latter with the point thereof resting against the surface of the steel, means to move said guide to cause the tack-point to travel along the said surface and find the tack-hole in the steel, jaws in connection with said guide to center the tack-point, and means to open and close said jaws, one of the jaws being yielding to give way to the resistance when the tack enters the tack-hole in the steel, substantially as described.

16. In combination, supports for a steel, a guide having a sloping or inclined passage to receive a tack and support the latter with the forwardly-inclined point thereof resting against the surface of the steel, means to move said guide to cause the tack-point to travel along the said surface and find the tack-hole in the steel, jaws in connection with said guide to center the tack-point, and means to open and close said jaws, one of the jaws being yielding to give way to the resistance when the tack enters the tack-hole in the steel, substantially as described.

In testimony whereof we affix our signatures in presence of two witnesses.

CHARLES B. RICH.
JOHN REED.
